GUMMED TEAR STRIP

Carroll V. Walters, Kansas City, Mo., assignor
of one-fourth to Claude A. Carlet and one-
fourth to Louis Orlando, Sr., both of Kansas
City, Mo.

Application June 18, 1934, Serial No. 731,052

1 Claim. (Cl. 229—86)

This invention relates to container opening construction of that class employing a thread or cord, or the like, which when subjected to a pulling action applied to one end of the thread 5 rips the container and my object is to produce an opener for envelopes or other containers of paper or easily rupturable material, which operates dependably and efficiently, can be applied in the course of manufacture of the envelope or the 10 like, without appreciably retarding the speed of production or appreciably increasing the cost of the latter, and which is of simple and cheap construction.

With the object mentioned in view, the invention 15 consists in certain novel and useful features of construction and organization of parts as hereinafter described and claimed; and in order that it may be fully understood, reference is to be had to the accompanying drawing, in which:—

20 Figure 1 is an inner face view of an envelope blank as same appears equipped with a thread-equipped ripping tape before the bottom and end flaps are folded over and secured together as indicated by dotted lines.

25 Figure 2 is an inner face view of the envelope as it appears after its top flap has been closed and the envelope has been ripped open along the bottom and end margins by the thread and then unfolded, the envelope in this condition exposing any printed matter should such have been applied upon its inner face prior to the folding of the bottom and end flaps.

30 Figure 3 is an enlarged fragmentary perspective view of the tape. Figure 4 is a similar view of a modified form of the tape.

35 Figure 5 is a view showing the tape slitted near one end and notched near the other end, as alternate modes for facilitating bending of a stout tape for use particularly with a cardboard container.

40 Figure 6 is a modified form of tape composed of a series of tape sections having a thread common to all the sections.

45 Referring now to the drawing, 1 indicates an envelope, shown as of conventional type, but which may be of other than rectangular contour, or it may be in the form of a box, such as those for holding breakfast foods, or other products, and 2 indicates a flexible tape for holding a rip 50 thread, cord or wire 3. The tape is preferably of paper, having a gummed surface 4, and the thread or the like is placed on the gummed face for adherence thereto, extending longitudinally of the tape and preferably nearer one margin 55 thereof, than the other.

The thread-equipped tape is shown in two forms, Figures 3 and 4. In Figure 3, the tape is in two sections, the opposite edges of the sections being fastened together at opposite sides of the thread by the gummed surface; it being noted that part of the gummed surface is left exposed because one section of the tape is narrower than the other. In the other form, the thread is caused to adhere to the gummed surface of the tape, but is left with one side exposed.

5 The thread equipped tape, at properly disposed intervals, may be transversely slit at 5, from its exposed gummed edge to the thread, to facilitate bending at the bottom corners of an envelope or the like, or may be notched as at 6 for the same purpose, though where the tape is of thin material, its folding to effect changes of direction to accommodate particular containers, may be resorted to without slitting or notching it.

10 In the course of manufacture of envelopes, and while they are in the condition indicated by full lines, Figure 1, the thread-equipped tape is applied, that portion of the gummed surface exposed in Figures 3 to 5 and 6, being caused to 15 adhere to the envelope in close proximity to and parallel with the lines of junction of the front side with the back and end sections, so that when the sections mentioned are folded over and secured together to complete the envelope ready 20 for boxing and delivery to purchasers, the thread-equipped tape will be wholly within the envelope, and when the latter is sealed, will be inaccessible 25 except by tearing off a top corner of the envelope. If desired, one of the top corners of the envelope may be suitably marked or weakened as 30 common, to call attention to the point most convenient for effecting opening of the envelope. Tearing at such point followed by a pull on the thread, will insure that advertising matter 35 printed on the inner surface of the envelope, will be brought to the opener's attention.

40 Figure 2 indicates an envelope opened to expose its inner faces, after it has been ripped at the bottom and ends by the rip thread, the withdrawal of the latter leaving the ripped tape exposed where attached to the envelope.

45 In Figure 6, the tape is shown as composed of a series of spaced sections, having a thread in common. With this type, the bends at the lower 50 corners of an envelope can occur in the thread alone, but in such case, at the points where each bend is to be made, it is desirable to have the adjacent sections of the tape close together to insure that the interposed bent portion of the 55

thread shall lie snugly within the corner of the envelope.

From the above description and the drawing it will be apparent that I have produced a 5 thread-equipped tape possessing the advantages set forth as desirable, and it is to be understood that I claim all modifications thereof within the spirit and scope of the appended claim.

I claim:—

- 10 A container ripping tape, comprising a strip of flexible rupturable material having one gummed face, a rip thread extending longitudinally of

and upon the gummed face of the strip nearer to one side margin of the strip than to the other side margin and affixed in position by the adhesive, and a strip overlying the thread and engaging and adhering at both side margins to the 5 gummed face of the first-named strip, the second strip being narrower than the first to leave part of the gummed surface of the latter exposed for effecting attachment of the tape to a container.
